UNITED STATES PATENT OFFICE.

WILLIAM DE FREITAS, OF NEW YORK, N. Y., ASSIGNOR TO MUNICIPAL LIGHTING COMPANY, OF NEW YORK, N. Y., A CORPORATION OF NEW JERSEY.

DESIGN FOR AN ILLUMINATING-LAMP.

SPECIFICATION forming part of Design No. 36,320, dated May 12, 1903.

Application filed December 26, 1902. Serial No. 136,655. Term of patent 7 years.

To all whom it may concern:

Be it known that I, WILLIAM DE FREITAS, a citizen of the United States, residing in the city, county, and State of New York, have invented and produced a new, original, and ornamental Design for Illuminating-Lamps, of which the following is a specification, reference being had to the drawing accompanying and forming part of the same.

The illustration shows a side view of a lamp embodying my new design, which, as will be seen, has for its leading or material features a casing 1, a globe 2, and a base part 3. The casing consists of a body portion ribbed and expanded in an ornamental manner and surmounted by an enlarged portion 4. It also carries a flaring reflector 5. The casing 1 between the flaring reflector and the enlarged portion 4 has a plurality of narrow circumferential ribs or "beads" 6 and above the latter an expanded part 7 of larger dimensions than the aforesaid ribs 6. Between the

part 4 and the expansion 7 is a continuous series of ornamental apertures or perforations 8, extending entirely around the body. Below the reflector is the transparent globe of a suitable conformation 2. Below the globe is the ornamental base part 3, of substantially conical shape, formed by steps of angular and curved contour. The base also has a series of perforations 9, extending entirely around the same.

Having now described my invention, what I claim as new, and desire to secure by Letters Patent, is—

The ornamental design for an illuminating-lamp, as herein shown and described.

In testimony whereof I have hereunto signed my name in the presence of two witnesses.

WILLIAM DE FREITAS.
